DESIGN FOR A COMBINED SOLE AND HEEL

Francis X. Lipari, New York, N. Y.

Application March 27, 1942, Serial No. 106,341

Term of patent 3½ years

To all whom it may concern:

Be it known that I, Francis X. Lipari, a citizen of the United States of America, residing in New York city, county of New York, and State of New York, have invented a new, original, and ornamental Design for a Combined Sole and Heel, of which the following is a specification, reference being had to the accompanying drawing, forming part thereof.

Fig. 1 is a top plan view of a combined sole and heel showing my new design.

Fig. 2 is a side elevational view thereof.

I claim:

The ornamental design for a combined sole and heel, substantially as shown.

FRANCIS X. LIPARI.
